TAPERED DISPOSABLE LIGHTER

Willem Beijering, Zweelo, Netherlands, assignor to Gebrs.
Van Poppel N.V., Assen, Netherlands, a corporation of the Netherlands

Filed Mar. 6, 1969, Ser. No. 16,096

Term of patent 14 years

Int. Cl. D27—05
U.S. Cl. D48—27

FIG. 1 is a side elevation of a tapered disposable lighter showing my new design;

FIG. 2 is a front elevation of said lighter;

FIG. 3 is a back elevation of said lighter;

FIG. 4 is a top elevation of said lighter; and

FIG. 5 is a bottom elevation thereof.

I claim:

The ornamental design for a tapered disposable lighter, as shown.
